ELECTRICAL COIL TESTER

Anthony G. Brown, Lakewood, Ohio, assignor, by
mesne assignments, to Jack & Heintz Precision
Industries, Inc., Cleveland, Ohio, a corporation
of Delaware

Application March 22, 1944, Serial No. 527,530

1 Claim. (Cl. 175—183)

1

This invention relates to an electric coil tester and has as its object to provide a coil tester of rugged construction capable of rendering a visual indication, without the use of delicate and sensitive instruments and the like, of a short circuited turn or turns in coils to be tested.

A preferred embodiment of the invention is illustrated in the accompanying drawing in which the single figure is a view in side elevation, with certain parts broken away, of a coil tester constructed according to the principles of the invention.

The operating parts of the mechanism are carried by an insulating base 1 in a housing 2 having a platform or shelf 3 adapted to support a coil 4 to be tested. Supported by the base 1 between a pair of angle irons 5 is a stack of E-shaped laminations 6, the completed stack having a central exciting leg 7, end legs 8 and 9, and short and long arms 10 and 11 respectively. The magnetic circuits are completed through a movable laminated arm or armature 12 magnetically linking the upper ends of the three legs 7, 8 and 9. The armature 12 is loosely mounted on a loose pivot 13 on a pair of standards 14 and is biased to the open position shown in full lines by a spring 15. A pair of standards 16 furnish pivotal support for a shaft 17 carrying a cam 18 and an operating handle 19. All of the aforementioned structure is contained within the housing 2 with the exception of the handle 19 which extends outside of the housing on its shaft 17 for manipulation in order to cam the armature 12 downwardly firmly against the legs of the magnetic circuit in its broken line position.

The upper ends of the laminated legs 7, 8 and 9 may be riveted as indicated by the numeral 20, and the lower extremities of the arm portions 10 and 11 may be clamped by bolts 21 which also serve to mount the laminated structure between the angle irons 5, the bolts 21 being located outside of the active magnetic circuits. The laminations of the armature 12 may be riveted, bolted or soldered together, the latter being at present preferred, with the solder applied only to the end portions outside of the active magnetic circuits.

In practice, the central leg 7 is preferably ground off to a level very slightly below the tops of end legs 8 and 9, and the pivot 13 has sufficient looseness so that the action of the cam 18 will insure a firm contact between the armature 12 and the ends of the legs 8 and 9. A slight gap between the armature 12 and the central leg 7 is not objectionable. The central leg 7 carries

2

an exciting coil 25 adapted to establish one magnetic circuit through the short arm 10, the leg 8, and a portion of the armature 12, and a second magnetic circuit through the long arm 11, the leg 9, and another portion of the armature 12. The short arm 10 carries a balance coil 26 and the long arm 11 carries a balance coil 27, these two coils being connected by means of wires 28, 29 and 30 in series opposition in circuit with a neon lamp 31.

To compensate for the unequal flux distribution resulting from the unequal lengths of the arms 10 and 11 in the preferred embodiment, the balance coil 26 is wound with 575 turns and the balance coil 27 is wound with 600 turns. This relationship is effective to produce an unbalance of approximately 25 volts between the coils 26 and 27 which is well below the ignition voltage of 50 volts of the lamp 31. If the test coil 4 contains no short circuited turns, the magnetic circuit is not affected by the presence of the coil and the neon lamp will not light. The values chosen are such that a one turn short circuit of number 15 B and S gage wire in the coil 4 produces an unbalance of approximately 300 volts between the coils 26 and 27 which produces a visual indication in the lamp 31. In order to provide a compact device, this tester is designed to operate on 500 cycles per second; however it can be readily modified by one skilled in the art to give satisfactory results on a 60 cycle supply.

The above values are cited not in a limiting sense but merely to illustrate the principles of the invention in accordance with the patent statutes so that one skilled in the art can make and use the same. For best performance the electric and magnetic circuits must be designed carefully with respect to the no load permeability of the magnetic circuit and the maximum unbalance of the electric circuit that can be tolerated with a given neon bulb, as will be readily understood by those skilled in the art.

Coil 25 may be designed to operate on voltages from 115 to 460 volts and frequencies of from 45 60 cycles per second to 500 cycles per second, inclusive. In theory, the placing of a short circuited turn of copper wire around the leg 9 of the magnetic circuit causes more current to flow in the exciting coil 25 in order to tend to maintain the flux constant in the test leg, in a manner similar to the short circuiting of the secondary of a transformer. This additional flow of current in the exciting coil sends more flux through the balance coil 26, thus increasing its induced voltage. The voltage in coil 27 remains

3

approximately the same, the increased difference in voltage between the two coils being of a sufficient magnitude to ignite the neon bulb.

In the illustrated embodiment the magnetic circuit is purposely unbalanced in the manner described to increase the window area in the coil testing side. This unbalance is partially compensated for by the difference in turns in the balance coils, but the unbalance must not be allowed to become excessive if a high degree of sensitivity is desired. It is therefore desirable to remove only sufficient turns from the coil 26 to bring the voltage differential between coils 26 and 27 safely below the ignition voltage of the bulb.

The amount of voltage unbalance produced in the indicating circuit for a single short circuited turn depends upon the current flowing in the short circuit path, whereby it is apparent that coils of relatively fine wire may be tested, as well as coils of wire larger than the No. 15 wire referred to. In testing different coils in this manner it is not necessary to make any changes or adjustments inasmuch as the neon lamp will function satisfactorily on any voltage within a wide range above its ignition voltage. Likewise, the unexpected presence of a number of short circuited turns in a test coil will cause no injury to the apparatus.

This feature offers a distinct advantage over coil testers employing delicate meters subject to injury if overloaded. The present coil tester is thus seen to be electrically as well as mechanically rugged, and well adapted to use by unskilled operators, while at the same time being always operative at its maximum sensitivity.

An advantage contributing to the rapid and efficient testing of coils by unskilled operators is that the only indication to be interpreted is the observation as to whether the lamp 31 lights or does not light when the handle 19 is rotated to clamp the armature 12 in its lower position. The device is designed for production use to facilitate the rapid testing of a large number of coils with a minimum of manual effort and manipulation.

Various changes in the construction and arrangement may be made, and all such modifications are included in the invention, the same be-

ing limited only by the scope of the appended claim.

I claim:

5 A coil tester comprising a laminated iron core having a central exciting leg and a pair of end legs forming a divided magnetic circuit, a stationary upright and a laminated armature pivoted thereto adjacent one of said end legs, spring means biasing said armature out of engagement with all of said legs manually operable cam means bearing upon said armature between said end legs for moving said armature into engagement with all of said legs to establish iron paths for said magnetic circuits, an exciting coil on said central leg for producing an alternating flux in said magnetic circuits, a pair of balance coils on said end legs connected in opposition, the cores of the coils being substantially in the form of a capital "E" whereby said armature is adapted to engage the cores of all three legs to close the magnetic circuit and a neon lamp connected in series with the coils which are connected in opposition with said balance coils, said balance coils being unbalanced only to such an extent that the difference in the voltages thereof is less than the ignition voltage of said lamp so that upon energization of said exciting coil ignition of said lamp is prevented in the absence of a short circuited turn in a coil to be tested and cause the ignition of said lamp when said test coil contains at least one short circuited turn.
